UNITED STATES PATENT OFFICE

156,328

COMBINATION COWL AND INSTRUMENT PANEL FOR AUTOMOBILES

Otis N. Farley, Lynden, Wash.

Application September 27, 1946, Serial No. 133,627

Term of patent 14 years

(Cl. D14—6)

To all whom it may concern:

Be it known that I, Otis N. Farley, a citizen of the United States of America, residing at Lynden, in the county of Whatcom and State of Washington, have invented a new, original, and ornamental Design for a Combination Cowl and Instrument Panel for Automobiles, of which the following is a specification, reference being had to the accompanying drawing, forming a part thereof, where-in:

Figure 1 is a perspective view of a combination cowl and instrument panel for automobiles attached for use, showing my new design, the dot-and-dash line showing being for illustrative purposes only.

Figure 2 is a view looking at one end of the combination cowl and instrument panel.

Figure 3 is a view of the opposite end of the combination cowl and instrument panel.

Figure 4 is a front view.

Figure 5 is a top plan view.

Figure 6 is a rear view of the combination cowl and instrument panel on a reduced scale.

I claim:

The ornamental design for a combination cowl and instrument panel for automobiles, as shown and described.

OTIS N. FARLEY.
